UNITED STATES PATENT OFFICE.

CHARLES G. PELTIER, OF ONTONAGON, MICHIGAN.

COMBINED HAIR BRUSH AND COMB.

1,303,720.

Specification of Letters Patent. Patented May 13, 1919.

Application filed April 3, 1918. Serial No. 226,482.

To all whom it may concern:

Be it known that I, CHARLES G. PELTIER, a citizen of the United States, residing at Ontonagon, in the county of Ontonagon and 5 State of Michigan, have invented new and useful Improvements in Combined Hair Brushes and Combs, of which the following is a specification.

This invention is an improved combined 10 hair brush and comb, the object of the invention being to provide an improved article of this kind, which can be used either as a comb or as a brush, which is simple in construction and which can be readily manufactured at small cost.

The invention consists in the construction and arrangement of parts hereinafter described and claimed.

In the accompanying drawings:—

20 Figure 1 is a side elevation, parts in section illustrating the improvement, the comb being in inoperative position.

Fig. 2 is an edge view of the same with the comb in operative position.

25 The brush is provided with the usual handle 2. On the flat face of the back of the brush, at diametrically opposite points are secured the lower flanged ends 3 of spring standards 4. The standards are provided with side walls 5 which gradually decrease in width from the outer to the inner ends of the said standards, and the said standards adjacent to their outer ends are provided each with an opening.

35 The comb is indicated by the numeral 6 and has its ends provided with outstanding pivots 7, arranged adjacent to what may be termed the outer corners of the said comb, and which pivots pass through the 40 referred to openings in the standards 4.

The sides or flanges 5 embrace the sides of the end teeth of the comb when the latter is in inoperative position, as illustrated in Fig. 1 of the drawings. A lateral pressure

upon the comb causes the ends of the comb 45 to ride over the inclined outer edges of the flanges 5, also causing the standards 4 to spring away from each other. The pivots 7 are of a length sufficient to at all times retain the same in the openings in the standards, and when the comb is brought to operative position, as illustrated in Fig. 2 of the drawings, the standards will spring inwardly toward each other and toward the ends of the comb, the widened portions of 50 the flanges 5 holding the comb in this position, the said standards, and the flanges 55 thereof holding the comb also in inoperative position, as will be understood.

What is claimed as new is:

1. In combination with a brush, resilient comb holding means on the back of the brush, arranged at right angles thereto and having side walls at their outer ends on their opposing sides, a comb having pivots 65 at its ends mounted in the outer ends of the comb holding means and adapted to be turned thereon to either projected or withdrawn position, the side walls of the comb holding means serving to engage and hold 70 the comb in either of such positions.

2. In combination with a brush, resilient comb holding means on the back of the brush arranged at right angles thereto and having side walls which gradually decrease 75 in width from the outer to the inner ends thereof so that their inner ends are of a width approximately equaling that of the transverse walls thereof, a comb having pivots at its ends mounted in the outer end 80 of the comb holding means and adapted to be turned thereon to either projected or withdrawn position, the side walls of the comb holding means serving to engage and hold the comb in either of such positions. 85

In testimony whereof I affix my signature.

CHARLES G. PELTIER.
